(57) **CLAIM**

The ornamental design for a display structure group, as shown and described.

DESCRIPTION

FIG. 1 is a top front perspective view of a display structure group showing the claimed design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top front perspective view of another embodiment of a display structure group showing the claimed design;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a top front perspective view of another embodiment of a display structure group showing the claimed design;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

The broken lines in the figures show portions of the display structure group that form no part of the claimed design.

1 Claim, 17 Drawing Sheets

Related U.S. Application Data

Dec. 8, 2015, now Pat. No. Des. 790,260, which is a continuation of application No. 29/534,157, filed on Jul. 27, 2015, now Pat. No. Des. 769,651, which is a continuation of application No. 29/499,677, filed on Aug. 18, 2014, now Pat. No. Des. 734,965, which is a continuation of application No. 29/432,724, filed on Sep. 19, 2012, now Pat. No. Des. 713,658.
